UNITED STATES PATENT OFFICE.

FRANK L. LARAVA, OF WORCESTER, MASSACHUSETTS, ASSIGNOR TO CULVER STEARNS MANUFACTURING COMPANY, OF WORCESTER, MASSACHUSETTS, A CORPORATION OF MASSACHUSETTS.

DOME LAMP.

Application filed June 4, 1926. Serial No. 113,801.

This invention relates to an electric lamp support which is capable of general use, but particularly adapted for the dome lamp of an automobile.

5 The principal objects of the invention are to provide a mounting for the incandescent lamp in which the casing for the lamp and associated parts constitute all the springs necessary so that the ordinary springs employed are eliminated; and to provide a construction in which the parts can be mounted without the use of soldering or welding, and thus decrease the cost in two ways.

10 Other objects and advantages of the invention will appear hereinafter.

Reference is to be had to the accompanying drawings, in which—

Fig. 1 is a bottom plan view of the lamp with the glass underneath removed;

20 Fig. 2 is a sectional view on the line 2—2 of Fig. 1, showing the glass and its supporting parts in dotted lines;

Fig. 3 is a view looking at the lamp socket in the direction of the arrow 3 in Fig. 2; and

25 Fig. 4 is a sectional view on enlarged scale of the support for the lamp and electrical connections therefor.

Although capable of other uses, I will describe this invention as applied to a dome lamp for an automobile. In this case the dome proper or reflector 10 is formed of sheet metal, as for example, tin, and it has the usual shape in general of such a reflector. It is provided with a surrounding flat flange 11 by which it is secured in position in the roof of a car and a glass is mounted below it as indicated in dotted lines in Fig. 2.

30 For the purpose of securing the electrical connections in place, I bend the sheet metal dome or reflector 10 inwardly to form a flat wall 12. I provide a perforation through this wall 12 and on opposite sides I place two insulating washers 13 and 14. The electrical connection is made to a metallic member 15 which passes through the opening in the wall 12 and the washers between the flange and the body 17 of this member.

45 There is a conical opening 18 extending through this member 15. The wire conductor is secured in position by a screw 19 with a head covering the entire base of the member 15.

50 55 For holding the lamp I provide a bracket

22 having a socket piece 21, all of sheet metal, like tin. This bracket is secured in position on the dome by rivets 23 so that no soldering or welding has to be employed. This socket piece 21 projects at an angle 60 from the bracket 22 which is in contact with the reflector or dome 10. It is located normally in the position shown in full lines in Fig. 2, but when the lamp base 20 is inserted in it, it is forced out to the dotted line position by the pressure of the metallic lamp base against the interior of the conical opening 18 to make a good contact at this point. In this way by utilizing the resiliency of the socket piece 21 and opposing it by the resiliency of the dome 10 at the rear, the lamp is held yieldingly in position, and no other springs are required. The lamp base 25 is, of course, provided with the usual pin 26 for entering a notch 27 in the edge of the 75 socket piece 21 which allows the lamp to be pushed in and turned slightly as usual. Then it will be held in position resiliently but securely. Current is conducted to and from the lamp by the electric wire 29 held in position by the head of the screw 19 and by a wire 30 connected with the dome 10 by a screw 31. The dome is connected with the lamp by the pin 26.

80 It will be seen from the description that 85 the expense of the device is reduced by utilizing the resiliency of the dome and base to take the place of springs and that the expense of soldering, welding, etc., is entirely eliminated. In this way the lamp is made 90 much less expensively than has been the case heretofore without impairing its efficiency.

Although I have illustrated and described only a simple form of the invention and shown it as applied only to a dome lamp I 95 am aware of the fact that modifications can be made therein by any person skilled in the art, and that the same principle can be applied to other forms of lamps, without departing from the scope of the invention as 100 expressed in the claims. Therefore, I do not wish to be limited in this respect, but what I do claim is:—

1. As an article of manufacture, a lamp comprising a reflector constituting a casing 105 for the lamp and having secured to the wall thereof a member for conducting the electricity to the lamp, and a socket piece for the lamp formed of sheet material and secured to the casing and set so that when the 110

lamp is introduced through it into contact with said conducting member it will, by its own resiliency and that of the casing, hold the lamp in position.

5. 2. In an electric lamp, the combination with a thin metal casing having a perforated flat wall, of electric conducting means secured to the casing through said perforation and insulated therefrom, and a socket piece 10 secured to the casing, formed of resilient material, and having a perforation for receiving the base of a lamp, said socket piece being normally located in a position to press the lamp base against the electric conducting 15 means with yielding pressure.

3. In an electric lamp, the combination with a concave sheet metal casing, the inside surface of which constitutes a reflector, said casing having an electric terminal thereon

for an electric lamp, of a sheet metal socket 20 piece for the lamp having a perforation riveted to the casing or reflector for holding the lamp against a conductor.

4. In a dome light, the combination with a concave tin reflector having a spot on the 25 wall bent in, flattened, and perforated, insulating washers on both sides of the flattened spot, a conducting member extending through said perforation and washers and fixed thereto and having a conical opening, 30 a bracket on the reflector having a socket piece for a lamp socket for pressing the lamp socket against the inner surface of the conical opening to make a contact, and a 35 conductor fastened to the reflector.

In testimony whereof I have hereunto affixed my signature.

FRANK L. LARAVIA.
